EXTENSIBLE DRILL COLLAR

Julius S. Beck, Long Beach, Calif., assignor, by mesne assignments, to J. Ed Hill, Inc., Houston, Tex., a corporation of Texas

Filed Feb. 20, 1958, Ser. No. 716,404

4 Claims. (Cl. 175—300)

This invention relates to extensible devices for connection in drill strings when drilling oil and gas wells. Generally, such devices are for maintaining optimum weight on drill bits and for jarring either up or down when required during rotary drilling operations. The optimum weight on the drill bit is accomplished by adding a required number of drill collars to the string below the present extensible device for continuing the vertical direction of the bore hole. The jarring action referred to is applicable to both vertical and directional drilling.

Since the flexibility of a drill string increases with its increase in length, the deeper the bore hole the more difficult it is to control the course of the bit downwardly in the earth. During drilling operations, various impediments are encountered such as angular formations, boulders, crevices and pressures, all of which tend to change the course of the bit from its intended direction. In order to accurately control the bit it is desirable, from time to time, to apply and relieve longitudinal forces in the drill string at a point well below the earth's surface.

An object of the invention is to provide an improved extensible device for use in a drill string, and which device is capable of multiple operations for meeting various requirements during a drilling operation.

A particular object of the invention is to reduce drilling time by reason of overcoming obstacles without withdrawing the drill string from the hole for attaching special tools.

Another object is to provide means for substantially uninterrupted drilling even though the drill string below the present device is subjected to cave-ins or other binding forces, such as the accumulation of drill solids in the bore hole.

A further object is to provide, in addition to the foregoing, an extensible and contractible link in a drill string, which link will accommodate the action of waves when used on a drilling barge.

A particular object is to provide a device of the described class without threads and thereby prevent the device from coming apart in a bore hole even though subjected to reverse rotation of the drill string or the sudden release of accumulated torque therein.

Another particular object is to provide an extensible bit control device for operation in a drill string below the earth's surface and which device is capable of being locked and unlocked relative to the extensible length thereof, yet one in which it is not necessary for the operator to know the exact extended or contracted position of the device for its successful operation.

A further object is to provide, in a suspension drilling device, a reserve extension means for jarring or spudding even after the bit has drilled off; that is, when the pipe has been extended for drilling a maximum depth before the upper drill string is lowered for additional drilling, in which instance the entire weight of the string is on the weight indicator and the drill bit is ineffective.

2

A still further object is to provide a slip joint in a drill string for accommodating elongation due to the suspended weight of the drill string above the present device.

In the accompanying drawings of exemplary forms of the invention:

FIGURE 1 is an elevational view of the invention connected in a drill string. (All forms of the invention herein shown and described have the same external appearance.) FIGURE 2 is an enlarged broken vertical sectional view of the upper portion of FIGURE 1 showing a preferred seal at the upper end of the mandrel and in sliding contact with the cylindrical inner surface of the upper body. FIGURE 2 also represents the inverted position of the lower portion of FIGURE 1 and the seal arrangement on the opposite end of the mandrel.

FIGURE 3 is a vertical sectional view of the upper cylindrical body on a reduced scale as compared with FIGURE 2. It is to be understood that the lower cylindrical body is substantially identical with the upper body, except it is inverted with respect thereto, and that one has internal drill pipe connecting threads while the other has external drill pipe connecting threads. (Note the box and pin arrangement in FIGURE 1.)

FIGURE 4 is a broken elevation of the upper portion of the mandrel and showing the seal, the seal expanding spring and spring holder in their assembled positions. Like FIGURES 2 and 3, FIGURE 4 also represents the lower portion of the invention in an inverted position.

FIGURE 5 is an elevational view of a mandrel for sliding and locking action in the upper and lower cylindrical bodies.

FIGURE 6 is an enlarged perspective view of one of the seals as illustrated in FIGURES 2 and 5.

FIGURE 7 is a broken elevation and sectional view showing the installed position of one of the two collar constructions for assembling the invention.

FIGURE 8 is a broken perspective, shown in vertical section, of the upper end of the lower mandrel and particularly showing an arrangement of lugs in the upper end thereof for receiving the collar assembly.

FIGURE 9 is a perspective view of the impact collar forming a part of the collar assembly.

FIGURE 10 is a perspective view of a locking sleeve, mounted on the impact collar.

FIGURE 11 is an enlarged transverse section taken on line 11—11 of FIGURE 4.

FIGURE 12 is an enlarged transverse section taken on line 12—12 of FIGURE 5.

FIGURE 13 is a transverse section taken on line 13—13 of FIGURE 8.

FIGURE 14 is an elevational view of a mandrel similar to FIGURE 5 but showing a modified form of the invention having a different arrangement of mandrel lugs thereon.

FIGURE 15 is a broken elevational view of a mandrel and showing a further modified form of the invention by reason of the arrangement of mandrel lugs thereon.

FIGURES 5A through 5F are schematic views illustrating some of the various positions of mandrel lugs relative to body lugs as in connection with the preferred form of the invention. (See FIGURE 5).

FIGURE 14A is a schematic view of a typical arrangement of mandrel lugs and body lugs in the first referred to modified form of the invention. (See FIGURE 14).

FIGURE 15A is a schematic view of a typical arrange-

ment of mandrel lugs and body lugs in the last referred to modified form of the invention. (See FIGURE 15.)

As shown in FIGURE 1, upper and lower cylindrical bodies 20 and 21 are connected with adjacent lengths of drill pipe 22 and 23 in a drill string. Although the complete drill string is not shown, it is to be understood that the present device is located between the upper and lower ends thereof and that drill collars, not shown, are connected in the drill string at desired locations. Preferably, the outside diameters of the cylindrical bodies 20 and 21 are large enough that the present device may be considered a special drill collar. As will become apparent as the description proceeds, the bodies 20 and 21 are identical in their construction except one (20) is provided with internal pipe connecting threads 24, whereas the other (21) has external pipe connecting threads 25 in accordance with the usual practice of joining drill pipe. The upper and lower bodies 20 and 21 slidably receive opposite ends of a tubular mandrel 26 having limited relative rotation therein and hereinafter described in detail.

Referring now to FIGURE 3, the upper body 20 includes the referred to pipe threads 24 in its upper end, an axial passage 27 therebeneath large enough to accommodate instruments lowered on wire lines, and a hydraulic chamber 28 of enlarged diameter beneath the axial passage. Immediately below the hydraulic chamber 28, the axial diameter is further increased, as at 29, to provide a shoulder 65 and vertical rows of spaced body lugs 30 are provided on opposite sides of the body portion 29 for coaction with mandrel lugs 31 on the outer surface of the mandrel 26 near the ends of the latter. The oppositely arranged vertical rows of body lugs 30 are shown in FIGURES 8 and 13 in connection with detailed illustrations of the lower cylindrical body 21.

The mandrel lugs 31 are aligned in vertical groups on opposite sides of the mandrel 26 and are spaced for engagement between the body lugs 30. As viewed in FIGURE 5, the mandrel lugs 31 are round at their left ends and are joined by a vertical rib 32 extending along the right side of each group of mandrel lugs. It is to be noted that the distance between the outermost lugs 31 of each group of mandrel lugs is less than the distance between the outermost lugs of each group of body lugs 30.

Referring now to FIGURES 2, 4 and 6, a cylindrical seal 33 is provided at each end of the mandrel 26. The seals 33 herein shown and described, together with their assemblies for constantly urging the seals against the wall of the hydraulic chamber 28, are shown and described in my prior patents, Nos. 2,819,878 and 2,819,879, both issued January 14, 1958. Each cylindrical seal 33 is in sliding contact with a cylindrical hydraulic chamber 28 and is tapered at its inner end for engagement with a correspondingly tapered surface 34 in each end of the mandrel 26. The seals 33 are secured in place by means of circular shoulders 35 around the tapered portions of the seals, and which shoulders are engaged in circular grooves 36 in the mandrel tapers 34. The outer ends of the seals are inwardly tapered, as at 37, where they receive correspondingly shaped rings 38 of semi-resilient material, such as rubber impregnated laminated fabric. Outwardly of the rings 38 there are shouldered spring holders 39, the end surfaces 40 of which are shaped to engage the rings 38 and the opposite shoulder surfaces are shaped to receive the ends of coiled compression springs 41. There is a relatively thin integral tubular extension 42 on the inner end of each spring holder 39 and which extension engages the inner diameter of each ring 38 and seal 33. The purpose of the extensions 42 is to prevent the seals from becoming constricted when subjected to high pressures, as for example, in deep wells where the circulating fluid pressures are relatively high. The ends of the springs 41 opposite the spring holder 39 are engaged by shouldered removable spring holders 43 shaped to fit the ends of the hydraulic chambers 28. The

axial passage diameters 44 and 45 of the spring holders 39 and 43 are preferably as large as the axial body passages 27. Set screws 46 in the sides of the holders 39 and 43 maintain the springs 41 in their assembled positions as shown in FIGURE 4.

All of the illustrated forms of the invention are held in coactive relation by collar assemblies, generally designated by the numeral 47 and shown in detail in FIGURES 7, 9 and 10. FIGURE 7 shows the collar assembly 47 in section, and FIGURE 8 shows an arrangement of inner and outer body lugs 48 and 49 as in opposing ends of both bodies 20 and 21. The collar assembly 47 is comprised of two primary components, an impact collar 50 and a locking sleeve 51, the adjoining ends of which have interfitting tapers 52 and 53. Since the assembled locations of the collars 50 and sleeves 51 on the mandrel 26 are inwardly of the mandrel lugs 31, the collars and sleeves are longitudinally split along opposite sides, as at 54 and 55, to facilitate assembly. Preferably, the adjoining edges 54 and 55 of the collars 50 and 51 are provided with coacting notches and projections 56 and 57, for holding the respective halves thereof against longitudinal displacement when inserting the collars and sleeves in the ends of the bodies 20 and 21. An annular shoulder 58 in each body 20 and 21 engages the lugs 31 at the inner end 59 of the collar 50; similarly, a shoulder 60 around the collar 50 at the base of the taper 52 engages the inner end 61 of the sleeve 51.

The inner and outer lugs 48 and 49 in the ends of the bodies 20 and 21 respectively engage lugs 62 and 63 on the collar 50 and sleeve 51. As shown in FIGURE 8 the pairs of body lugs 48 and 49 are oppositely arranged with relation to each other. A flange 64 around the outer end of the sleeve 51 engages the outer edges of the outer body lugs 49, but which flange is received within the body 20 or 21 and is flush with the end thereof.

When installing the collar assembly 47, the halves of the impact collar 50 are placed around the mandrel and inserted in the body 20 or 21. The collar 50 and lugs 62 thereon are first rotated to pass between the outer body lugs 49 and then further rotated to pass between the inner body lugs 48. Further rotation causes the impact collar lugs 62 to be positioned inwardly of the inner body lugs 48. Similarly, the two halves of the locking sleeve 51 are placed on the mandrel and are rotated so as to cause the lugs 63 thereon to fit beneath the outer body lugs 49. Set screws, not shown, may be employed through the body 20 or 21 to secure the impact collars 50 and sleeves 51 against rotation; however, it has been found that frictional engagement is ordinarily sufficient for this purpose.

Operation of the first described form of the invention has to do with various functions such as suspension drilling, jarring, spudding and determining whether or not a free point is above or below the present device. A typical position for suspension drilling is shown in FIGURE 5A and has to do with conventional clockwise rotation of the drill string as viewed from the earth's surface. Here, the clockwise rotation of the upper drill string 22 imparts the same rotation to the upper body 20, causing the body lugs 30 therein to engage the vertical rib 32 on the mandrel 26 which, in turn, causes the lower mandrel lugs 31 to interfit and engage body lugs 30 in the lower mandrel 21. A similar operating position is shown in FIGURE 5F, but wherein the outer end mandrel lugs contact shoulders 65 in the bodies 20 and 21 outwardly of the body lugs 30; thus, FIGURE 5F illustrates an operation where the bodies 20 and 21 are in their relative contracted positions. FIGURES 5C and 5B represent engagement of the upper body lugs 30 when the upper drill string 22 has been counter-rotated. These positions are used, for example, when jarring or spudding since the imparted counter-rotation through the mandrel 26 causes the lower vertical ribs 32 to make sliding contact with the lower body lugs 30. FIGURES 5D and 5E

show contracted and extended positions of the bodies 20 and 21 when the upper and lower mandrel lugs 31 are positioned for sliding action between upper and lower body lugs 30. This position is obtainable when there is no rotary action or torque imparted in the upper drill string 22 and which position is for spudding or for finding the free point (above or below the present device) when the drill string is stuck in the hole. The term "free point" designates a location of the drill string above or below the stuck portion, that is, a point or portion where the drill string is free in the bore hole.

The various described positions, FIGURES 5A through 5F are obtained by empirical tests by rotating, counter-rotating and raising and lowering the drill string. For example, the operator will know when the bit has drilled off in suspension drilling by increased weight on the weight indicator. The operator may readily position the device as shown in FIGURE 5A by first counter-rotating the upper drill string 22 to obtain a position as in FIGURE 5C, raising the drill string slightly so as to position the lower mandrel lugs intermediate the ends of the lower body lugs 30, and then rotating the upper drill string clockwise to cause the engagement as shown in FIGURE 5A. This position is preferred for suspension drilling since reserve jarring action may be obtained after the bit has drilled off. In the latter case, the operator counter-rotates the upper drill string 22 and obtains the position illustrated in FIGURE 5C; thus, the operator is in a position to spud or jar. Delayed action jarring is obtained, either up or down, by stretching or applying weight to the upper drill string before disengaging any of the mandrel lugs 31 from the body lugs 30.

The form of mandrel illustrated in FIGURE 14 has its upper mandrel lugs 31a directed to the right relative to its vertical rib 32a, whereas its lower mandrel lugs 31a are directed to the left relative to their vertical rib 32a. An operation of this form of the invention is illustrated in FIGURE 14A wherein both upper and lower mandrel lugs 31a are engaged with corresponding body lugs 30a during normal clockwise rotation. Among its several operations this arrangement provides up and down jarring as above referred to and is desirable during certain operations, such as reaming, and washover operations.

The mandrel 26b illustrated in FIGURE 15 is primarily intended for operations wherein full telescoping action is required; however, in view of the foregoing explanation, it will be apparent that this form of the invention is also adaptable for use in jarring and spudding operations by applying clockwise and counterclockwise rotation to the upper drill string and raising and lowering the same in the manner previously described. In FIGURE 15A the mandrel lugs 31b are disengaged from the body lugs 30b, and the vertical ribs 32b are in sliding contact with the latter.

In all forms of the invention, the contracted position of the present device is limited by contact of the outermost mandrel lugs 31, 31a or 31b with the shoulders 65 in the bodies 20 and 21. Similarly, the extended position of the device is limited by contact with the innermost mandrel lugs 31, 31a and 31b in contact with the impact collars 50.

The invention is not limited to the exemplary construction herein described but may be made in various ways within the scope of the appended claims.

What is claimed is:

1. The combination of a drill string including spaced upper and lower sections, and a drill collar interposed between and connecting said upper and lower string sections together for limited rotary and sliding movement of one section relative to the other, said drill collar comprising a tubular upper body secured at its upper end to the lower end of the upper string section, a tubular lower body secured at its lower end to the upper end of the lower string section, said upper and lower bodies being coaxial and having spaced adjacent ends, a tubular man-

drel having upper and lower end portions telescoped for limited rotational and sliding movement in the lower end portion of the upper body and in the upper end portion of the lower body respectively, sets of vertically spaced body lugs provided on the inner surface of the lower and upper end portions of the respective upper and lower bodies, sets of vertically spaced mandrel lugs provided on the outer surface of the upper and lower end portions of said mandrel, said mandrel lugs being selectively received in the spaces between the respective body lugs and said body lugs being selectively received in the spaces between the respective mandrel lugs upon rotation and sliding of said bodies relative to the mandrel whereby to vary the overall length of the drill collar, vertical ribs provided on the outer surface of the upper and lower end portions of the mandrel continguously with and at one side of the mandrel lugs in the respective sets, said body lugs when disposed in the spaces between said mandrel lugs abutting said ribs to prevent rotation of said bodies relative to said mandrel in one direction but permit rotation thereof in the relatively opposite direction for withdrawal of the lugs from their respective spaces, upper and lower split locking collars positioned on said mandrel in the respective upper and lower bodies and below and above the respective sets of mandrel lugs, coacting means provided on said collars and in said bodies for retaining the former at fixed locations in the latter, the lowermost and uppermost mandrel lugs in the respective sets being engageable with the respective upper and lower collars whereby to limit the extent to which said bodies may be slid away from each other on said mandrel, and inwardly projecting shoulders provided in said bodies above and below the respective sets of mandrel lugs, the uppermost and lowermost mandrel lugs in the respective sets being engageable with said shoulders whereby to limit the extent to which said bodies may be slid toward each other on the mandrel.

2. The device as defined in claim 1 together with a pair of tubular seals of resiliently compressible material provided at the upper and lower ends of said mandrel and engaging the inner surfaces of the respective bodies, and springs positioned in said bodies and abutting said seals for urging the latter laterally outwardly against the inner surfaces of the bodies.

3. In a drill string collar, the combination of a tubular body having a first end adapted for connection to a drill string section and an open second end, a tubular mandrel having one end portion thereof rotatably and slidably positioned in said body and projecting outwardly therefrom at said second end of the latter for connection to another drill string section, a set of longitudinally spaced body lugs provided intermediate the ends of said body on its inside surface, a longitudinal rib provided on the inside surface of the body at one side of and contiguously with said set of body lugs, a set of longitudinally spaced mandrel lugs provided on said one end portion of said mandrel, said mandrel lugs being selectively disposed in the spaces between said body lugs in engagement with said rib whereby to lock said mandrel against sliding in said body and prevent rotation of the mandrel in the body in one direction but whereby to permit rotation of the mandrel in the relatively opposite direction for withdrawal of the mandrel lugs from said spaces between the body lugs and facilitate sliding of the mandrel in the body, a split locking collar positioned in said body at a point between the body lugs and said second end of the body, means in the body and on said locking collar for retaining the collar at a fixed point in the body, said locking collar slidably receiving said mandrel and the adjacent mandrel lug in the set being engageable with the locking collar to limit the extent of outward sliding of the mandrel in said body, and an inwardly projecting shoulder provided in said body at a point between said first end of the body and said body lugs, a mandrel lug

in the set adjacent said shoulder being engageable with the latter to limit the extent of inward sliding of the mandrel in said body.

4. The device as defined in claim 3 wherein said means for retaining said locking collar in said body comprise a set of circumferentially and longitudinally offset keeper lugs provided inside the body, and a set of circumferentially and longitudinally offset keeper lugs provided on said locking collar, said sets of keeper lugs being separably inter-engageable upon rotation and sliding of the 10

locking collar in the body whereby to prevent sliding of the locking collar in the body in both directions when said sets of keeper lugs are interlocked.
